UNITED STATES PATENT OFFICE.

FRANK L. SHELL, OF OMAHA, NEBRASKA.

VAPOR-HEATING SYSTEM.

1,186,446.

Specification of Letters Patent.

Patented June 6, 1916.

Application filed March 1, 1913. Serial No. 751,522.

To all whom it may concern:

Be it known that I, FRANK L. SHELL, a citizen of the United States, residing at Omaha, in the county of Douglas and State of Nebraska, have invented new and useful Improvements in Vapor-Heating Systems, of which the following is a specification.

The invention relates to heating systems for use in buildings and the like, and has for 10 an object to provide a vapor heating system wherein the products of condensation in the system and any air contained therein will be removed from the system in order to permit the vapor or steam to pass through the 15 system for the purpose of heating.

The invention embodies more particularly, a system oftentimes called a vacuum heating system and whereby a partial vacuum is formed in the system in order that 20 the vapor or steam can readily pass therein and properly perform its function of heating.

A further object of the invention is the provision of a vapor heating system in 25 which use is made of means having connection with the chimney of the boiler and which, when heated, will aid in the creation of a partial vacuum in the system.

In the further disclosure of the invention 30 reference is to be had to the accompanying drawings, constituting a part of this specification, in which similar characters of reference denote corresponding parts in all the views, and in which:

35 Figure 1 is a diagrammatic front elevation of the system; Fig. 2 is a fragmentary enlarged side elevation, showing the manner of arranging and supporting the controlling valves between the chimney and the boiler; 40 Fig. 3 is a vertical longitudinal sectional view taken through the valves; and Fig. 4 is a fragmentary plan view showing the position of the valves with respect to the chimney and boiler and the arrangement of the 45 exhaust pipe in the chimney.

Referring to the views, and more particularly to Fig. 1, I disclose a vapor heating system 10 consisting of a vapor or steam line 11 having connection, by means of suitable pipes 12, with the upper ends of radiators 13, a return line 14 being also provided and following substantially the same path as the vapor or steam line 11, the said return line having connection, by means of 50 pipes 15, with the lower opposite ends of the radiators 13, as shown, the vapor or steam 55

line 11 having connection with a boiler 16 by a pipe 11^a and provided with a flue 17 connecting with a chimney 18.

A drain pipe 19 forming a part of the return line and of which the pipes 15 also constitute a part has connection with the boiler 16 below the water line in the boiler and the return line 14 terminates in the drain pipe 19, as shown. An exhaust pipe 60 20 is arranged to extend vertically in the chimney 18, and interposed between the drain 19 and exhaust pipe 20 and connected thereto are a plurality of connected valve casings 21, 22, the valve casing 21 being 65 supported on the drain pipe 19 and the valve casing 22 having connection with the lower end of the exhaust pipe 20, a pipe 23 being 70 arranged to connect the valve casings 21 and 22. 75

The valve casing 21 includes a suitable cover 24 provided with a guideway 25 and in which is mounted to slide the upper end of a stem 26 forming a part of a valve 27 including a valve member 27^a normally reposing on a seat 28 formed at the upper end of the drain pipe 19 and adjacent the point where the drain pipe connects with the valve casing 21, a suitable float 29 being also carried on the valve stem 26 as shown in Fig. 80 3, and constituting a part of the valve 27.

The valve casing 22 includes a cover 30 having an integral depending socket 31 in which is threaded a stem 32 forming a part of a thermostatic valve 33 and which includes a 85 90 thermostatic diaphragm 34 and a valve member 35 depending from and rigid with the diaphragm 34, with the said valve member adapted to repose on a seat 36 formed in the casing 22 adjacent the point of connection of the pipe 23 with the casing. Now 95 it will be readily apparent that by providing the threaded connection between the stem 32 and socket 31 of the cover 30, the thermostatic valve 33 can be readily adjusted with 100 respect to the cover of the casing and the valve seat 36.

Now in the operation of the system disclosed it will be apparent that when the fire is started in the boiler 16, the steam or vapor 105 produced will pass through the vapor line 11 of the system and then pass into the radiators 13. The pipes 15 connecting the radiators with the return line 14 are provided with the usual globe valves 37 and if these 110 are open the usual products of condensation in the radiators and in the vapor line will be

forced into the return line 14 and then pass into the drain pipe 19 from which they will pass into the boiler 16 below the water line thereof. Now as the vapor in the vapor line advances therein and passes into the radiators the air contained in the vapor line and radiators will pass into the return line 14, but instead of passing into the boiler on account of the water seal at the point of connection of the drain pipe with the boiler, the air will pass upwardly into the valve casing 21 and on account of its pressure will move the valve member 27^a into open position so that the air will pass through the pipe 23 into the valve casing 22 which is normally in open position on account of the contractile action of the diaphragm 34 when not heated, and the said air will then pass into the exhaust pipe 20 extending upwardly in the chimney 18. Now it will be readily apparent that on account of the fire in the boiler the exhaust pipe 20 in the chimney 18 will be heated on account of the waste products of combustion passing up the chimney from the boiler. This heating of the pipe 20 will cause the air therein to become heated and pass upwardly in the pipe, thus creating a partial vacuum in the valve casings 21 and 22 and the return line 14 so that the heating of the pipe in the chimney will aid in exhausting the air from the system.

When the return has been exhausted from the system, as mentioned, it follows that the vapor which has now filled the radiators 13, will pass into the return line 14 on account of the pressure it has, and will in consequence pass into the casings 21 and 22, but when the vapor reaches the casing 22 the heat of the vapor will cause the diaphragm 34 to become heated and it will immediately expand, thus moving the valve member 35 into closed position to close the outlet of the pipe 23 and prevent any further vapor from passing into the casing 22. It will now be apparent that the operation of the system will be complete and that the heat of the vapor will of course heat the radiators and in this way heat the atmosphere of the rooms in the building in which the radiators are located. It will be readily seen that any products of condensation contained in the casing 21 or pipe 23 will tend to return to the drain pipe 19 and in order to prevent

any clogging in the casing 21 and pipe 23, I provide the float 29 carried by the valve 27 so that the products of condensation, returning to the drain pipe 19, will, through the medium of the float 29, raise the valve member 27^a from its seat 28 and permit the products of condensation to pass into the drain pipe.

From the foregoing description it will, therefore, be seen that with the vapor heating system described the usual water-hammer found in a great many systems will be prevented in view of the fact that the air contained in the system as well as the products of condensation therein are exhausted from the system as the vapor or steam advances therein and the products of condensation will follow a direct path back to the boiler while the air in the system will pass outwardly through the exhaust pipe 20 in the chimney 18, the provision of the valves 27 and 33 being adapted, however, to permit all products of condensation in the casings 21 and 22 and pipe 23 to return to the drain pipe and thence to the boiler and also prevent the steam or vapor for heating from passing into the exhaust pipe 20 in the chimney 18.

Having thus described my invention, I claim:

In a heater, in combination, a boiler, a radiator, a steam pipe connecting said boiler and radiator, an exhaust pipe connected to said radiator and having a curved offset at its lower end, a pipe section leading from said offset to below the water line of said boiler, a casing communicating with said pipe section above said offset, a valve in said casing closing said pipe section but adapted to be unseated by the fluid pressure therein, a float in said casing for unseating said valve, a second casing, a pipe joining both casings, a thermostatically controlled valve in the second casing closing the last-named pipe, and a heated exhaust pipe communicating with the second casing.

In testimony whereof I affix my signature in presence of two witnesses.

FRANK L. SHELL.
